UNITED STATES PATENT OFFICE.

ERNEST C. HEAD, OF ROCHESTER, NEW YORK, ASSIGNOR TO COLEBURN MACHINE TOOL COMPANY, OF FRANKLIN, PENNSYLVANIA, A CORPORATION OF PENNSYLVANIA.

OPERATING DEVICE FOR THE TURRETS OF MACHINE-TOOLS.

1,345,770.

Specification of Letters Patent.

Patented July 6, 1920.

Application filed November 10, 1917, Serial No. 201,241. Renewed February 24, 1919. Serial No. 278,935.

To all whom it may concern:

Be it known that I, ERNEST C. HEAD, a citizen of the United States of America, and a resident of Rochester, New York, have 5 invented a new and useful Improvement in Operating Devices for the Turrets of Machine-Tools, which invention is fully set forth in the following specification.

This invention relates to operating devices 10 for the turrets of machine-tools.

It has heretofore been proposed to mount the turret of a machine-tool on a fixed pivot and to provide gearing for rotating the turret upon said pivot to bring the tools successively 15 into operative relationship with the work, together with means for rigidly clamping and locking the turret in its adjusted position. It has also been proposed to provide, between the clamping member 20 and the turret, a rectilinearly movable housing splined on said pivot, said housing carrying part of the gearing for rotating the turret. Devices of this type heretofore constructed have been more or less complicated, 25 expensive to manufacture, and inconvenient in use.

It is an object of this invention to provide turret-operating means which is simple in construction, inexpensive to manufacture, 30 easy and convenient of manipulation, and efficient and certain in operation.

To this end, the invention comprises, broadly, the combination of a turret, a pivot on which said turret is rotatably mounted, a gear, preferably a bevel gear, rigidly connected with the turret, a housing non-rotatably mounted upon said pivot, and a pinion carried by said housing in mesh with said gear to rotate said turret, the axis of rotation 35 of the pinion preferably being inclined at an acute angle to the axis of the pivot. Said housing is mounted on the pivot for movement into clamping relation with the turret, and clamping means are provided, as 40 a nut on a threaded extension of the pivot, for so moving the housing; also means are provided for locking the turret in adjusted position, preferably in the form of a locking bolt designed to engage notches on the 45 turret.

The invention is capable of receiving a variety of mechanical expressions, one of which is shown on the accompanying drawing; but it is to be expressly understood

that the drawing is for purposes of illustration only and is not to be construed as a definition of the limits of the invention, reference being had to the appended claims for that purpose.

In said drawing:—

Figure 1 is a front elevation of a turret equipped with my improved operating devices;

Fig. 2 is a section through the turret-rotating device on the line 2—2 of Fig. 1;

Fig. 3 is a central vertical section through the turret and operating devices on the line 3—3 of Fig. 1.

Referring to the drawing, wherein the same characters of reference are used to designate corresponding parts in the several figures, the invention is shown as applied to the turret of a vertical boring and turning mill, but it is to be expressly understood that this application of the invention is for the purposes of illustration only, as the invention is of equal utility when applied to the turrets of other types of machine-tools.

The turret is shown at 1 and may be of any suitable construction, the details of the 80 turret forming no part of the present invention. Said turret is rotatably mounted on a pivot 2 carried by any suitable form of slide 3, said pivot being fixed with respect to the slide by any suitable means, as a pin 85 or pins 4. Also mounted on the pivot 2 is a sleeve 5 shown as provided at one end with a flange 6 rigidly connected to the turret 1, as by screws 7, and provided at its opposite end with a gear 8 shown as a bevel gear.

Also mounted on the pivot 2, and shown as carried by a reduced and threaded extension 9 thereof, is a housing 10 generally cup-shaped in formation and constituting a housing for the gear 8. Said housing 10 is 95 non-rotatably mounted on the pivot 2, any suitable means being provided, as the key 11, for preventing relative rotation of the pivot and housing. This housing is not attached in any way to the turret 1, but may move 100 rectilinearly, owing to the key 11, into and out of engagement with said turret.

Rotatably mounted in the housing 10 is an arbor 12 with its axis preferably at an acute angle to the axis of the pivot 2, any suitable bearing, as shown at 13, being provided for said arbor. The inner end of this arbor carries a pinion 14 in mesh with gear 8, and

the outer end of the arbor is provided with any suitable means for rotating the same, as the crank 15.

Any suitable clamping means for moving the housing 10 into clamping relation with the turret 1 may be provided. In the form shown, a nut 16 is rotatably mounted on the threaded extension 9 and provided with the operating handle 17, whereby, by rotation of said nut 16, said housing 10 may be advanced rectilinearly into clamping relation with the turret for securing the requisite rigidity of the turret when the tools carried thereby are in operation. A nut 18 may also be provided for limiting the backing off movement of nut 16.

Suitable means are also provided for locking the turret in its adjusted position. To this end, the turret 1 is shown provided with a locking ring 19 having locking notches in number corresponding to the number of tools carried by the turret 1. Rectilinearly movable in the slide 3 is a locking bolt 20 which is designed to engage the notches in the ring 19 and rigidly retain the turret in adjusted position. Said bolt 20 is provided with suitable means, as the hand-lever 21, for disengaging the same from the notches in the ring 19 and it may be provided with a spring for normally urging the bolt into engagement with said notches as disclosed in the patent to Frederick F. Clarke, No. 1,188,042, granted June 20, 1916.

In operation, the hand-lever 21 is manipulated to withdraw the locking bolt 20 from engagement with the notch in the locking ring 19 on the turret 1, and handle 17 is rotated to back the nut 16 off from clamping engagement with the housing 10. The turret may now be freely revolved on pivot 2 for bringing the desired tool into operative relation with the work. Such rotation is effected by turning the crank 15 which, through pinion 14 and gear 8, transmits the rotary movement to said turret. The turret having reached its proper position, locking bolt 20 is returned into engagement with the corresponding notch in ring 19 securely locking the turret in its adjusted position, and handle 17 is rotated to advance the nut 16 into engagement with the housing 10, which in turn slides on the pivot 2 to engage the turret 1, and rigidly clamp the same in position.

It will therefore be seen that, by the provision of the non-rotatable housing 10 and the pinion 14 carried thereby at an acute angle to the pivot and in mesh with the gear 8 rigidly connected with the turret, a rotating device for the same is provided which is simple in construction and particularly easy and convenient of manipulation. Also, by the combination of said turret-rotating device with the turret-locking and clamping devices employed, a turret-operating

device comprising the minimum number of parts is provided and one that is inexpensive to manufacture and exceedingly simple, efficient and certain in operation.

While the illustrated embodiment has been described with considerable particularity, it is to be expressly understood that the invention is not to be restricted to the precise details shown on the drawing but that the invention is capable of embodiment in a variety of forms, some of which will readily suggest themselves to those skilled in the art. Reference is therefore to be had to the claims hereto appended for a definition of the limits of the invention.

What is claimed is:—

1. In combination, a turret, a pivot on which said turret is rotatably mounted, a gear rigidly connected with said turret, a housing non-rotatably mounted upon said pivot, a gear member carried by said housing and rotatable on an axis intersecting the axis of said pivot at an acute angle, said gear member being in mesh with said gear, and means to rotate said gear member.

2. In combination, a turret, a pivot on which said turret is rotatably mounted, a bevel gear rigidly connected with said turret, a housing non-rotatably mounted upon said pivot, an arbor rotatably mounted in said housing with its axis intersecting the axis of said pivot at an acute angle, a pinion on said arbor in mesh with said bevel gear, and means to rotate said arbor.

3. In combination, a turret, a pivot on which said turret is rotatably mounted, a gear rigidly connected with said turret, a housing non-rotatably mounted upon said pivot, an arbor in said housing laterally disposed to said pivot and having its axis intersecting the axis of said pivot at an acute angle, a gear member on said arbor in mesh with said gear, and means to rotate said arbor.

4. In combination, a turret, a pivot on which said turret is rotatably mounted, a gear rigidly connected with said turret, a housing splined to said pivot, clamping means carried by said pivot for moving said housing into clamping relation with said turret, a gear member in mesh with said gear and mounted in said housing on an axis intersecting the axis of said pivot at an acute angle, and means to rotate said gear member.

5. In combination, a turret, a pivot for said turret provided with a screw-threaded extension, a gear rigidly connected with said turret, a housing splined to said pivot, a clamping nut carried by said screw-threaded extension for moving said housing into clamping relation with said turret, means for rotating said nut, a gear member in mesh with said gear and mounted in said housing on an axis intersecting the axis of

said pivot at an acute angle, and means to rotate said gear member.

6. In combination a turret, a pivot on which said turret is rotatably mounted, a gear rigidly connected with said turret, a housing non-rotatably mounted on said pivot, a gear member in mesh with said gear and mounted in said housing on an axis in-

tersecting the axis of said pivot at an acute angle, means to rotate said gear member, a locking bolt for engagement with locking notches on said turret, and means to operate said locking bolt.

In testimony whereof I have signed this specification.

ERNEST C. HEAD
